Primary Examiner — Sharon S Oum*(74) Attorney, Agent, or Firm* — Dickinson Wright PLLC; Andrew D. Dorisio(57) **CLAIM**

The ornamental design for a fan, as shown and described.

DESCRIPTION

FIG. 1 is a perspective view of a fan;

FIG. 2 is an enlarged bottom perspective view thereof, shown without the ceiling mount, fan blades and light fixture for completeness of illustration;

FIG. 3 is a top perspective view thereof;

FIG. 4 is a right side view thereof;

FIG. 5 is a front view thereof;

FIG. 6 is a left side view thereof;

FIG. 7 is a rear view thereof;

FIG. 8 is a top view thereof; and,

FIG. 9 is a bottom view thereof.

The broken lines depict portions of the fan and form no part of the claimed design.

1 Claim, 9 Drawing Sheets(56)
